BRACELET OR SIMILAR ARTICLE

Lillian Braun, 333 E. 51st St., Long Beach, Calif.

Filed June 1, 1961, Ser. No. 65,421

Term of patent 14 years

(Cl. D45—4)

Fig. 1

Fig. 2

Fig. 3

I claim:

The ornamental design for a bracelet or similar article, substantially as shown.
